(57) **CLAIM**

The ornamental design for a waste receptacle with lid, as shown and described.

DESCRIPTION

FIG. 1 is a front perspective view of a waste receptacle with lid showing our new design;

FIG. 2 is a rear perspective view thereof;

FIG. 3 is an exploded front perspective view thereof;

FIG. 4 is an exploded rear perspective view thereof;

FIG. 5 is a top view of the waste receptacle with lid;

FIG. 6 is a cross-section view of the waste receptacle with lid of FIG. 5;

FIG. 7 is a bottom view of the waste receptacle with lid;

FIG. 8 is a front elevational view of the waste receptacle with lid;

FIG. 9 is a rear elevational view of the waste receptacle with lid;

FIG. 10 is a right side elevational view of the waste receptacle with lid;

FIG. 11 is a left side elevational view of the waste receptacle with lid;

FIG. 12 is a top plan view of the waste receptacle with lid;

FIG. 13 is a bottom plan view of the waste receptacle with lid;

FIG. 14 is a front elevational view of the waste receptacle with lid;

FIG. 15 is a rear elevational view of the waste receptacle with lid;

FIG. 16 is a right side elevational view of the waste receptacle with lid;

FIG. 17 is a left side elevational view of the waste receptacle with lid; and,

FIG. 18 is a front perspective view of the waste receptacle with lid in an environment of an assay processing system. The broken lines shown in the figures are for the purpose of illustrating portions of the waste receptacle with lid and form no part of the claimed design. The broken lines showing an assay processing system in FIG. 18 are for the purpose of illustrating environment and form no part of the claimed design.

1 Claim, 18 Drawing Sheets
